UNITED STATES PATENT OFFICE.

SIMON DANCYGER, OF DAYTON, OHIO.

MAILING-WRAPPER.

SPECIFICATION forming part of Letters Patent No. 653,288, dated July 10, 1900.

Application filed September 3, 1897. Serial No. 650,438. (No model.)

To all whom it may concern:-

Be it known that I, SIMON DANCYGER, a citizen of the United States, residing at Dayton, in the county of Montgomery and State of

5 Ohio, have invented certain new and useful Improvements in Mailing-Wrappers; and I do hereby declare that the following is a full, clear, and exact description of the invention, which will enable others skilled in the art 10 to which it appertains to make and use the same, reference being had to the accompanying drawings, and to the letters and numerals of reference marked thereon, which form a part of this specification.

15 The invention relates to improvements in mailing-wrappers the features of which are the binding of the edges of a folded blank of paper by metallic clasps clenched in the free edges thereof.

20 The construction is illustrated in the accompanying drawings, in which—

Figure 1 is a front view of the device. Fig. 2 is a side view of the clasp. Fig. 3 is a transverse section of Fig. 1 as folded.

25 Like letters and numerals designate like parts in the several views.

The paper blank comprises two equal parts A A', which are creased for folding at the central line, as indicated by dots extending from 30 the top to the bottom. The several punctures 1 near the side and top and bottom edges in part A' are provided with the metallic clasps B. These are put in said punctures from the outside of said paper blank, and the point 2 is pressed down or clenched against the inner surface. The clasp is a narrow strip of metal, pointed as may be convenient, and comprises the inner end 2, bent down parallel with the body, and the free end 3 with the 35 curve 4 near its center, or without this, and said free end 3 adapted to be bent over to embrace the contiguous edge of said paper blank, and thereby unite the abutting edges, as shown at 3, Fig. 3. A slight bend in the

free end of the clasp (see 5, Fig. 3) would be 45 of advantage in entering the top section of said blank beneath the same where said free end is bent down against the inner surface of said blank.

In use the sections of the blank are brought 50 together and the free ends of the clasps are pressed down over the abutting edges. When all the clasps are closed down to get at the contents of the wrapper, it is only necessary to raise the free end of the clasp at one or both 55 ends. When two sets of clasps are arranged near the corners of the blank, the folding section can be released readily only by opening of the end clasps. A clasp or clasps may be clenched to the side edge of one section of 60 the blank and the clasps at the ends fastened to the other section.

The wrapper is adapted to inclose samples of merchandise or other matter which is flat and not bulky.

65 The normal condition of the side clasp is that of the end bearing against the inner surface of its section by the resiliency of the metal and when the contiguous section is entered beneath the same is retained in position.

70 Having fully described my invention, what I claim is—

As a new article of manufacture a mailing-wrapper comprising a folded blank of paper with abutting edges, and provided with metallic clasps on the three edges of one section of said blank, the other section being adapted to fold over and under the side clasps of the same and to have the other clasps bent over its end edges, substantially as described.

75 80 In testimony that I claim the foregoing as my own I affix my signature in presence of two witnesses.

SIMON DANCYGER.
